UNITED STATES PATENT OFFICE.

SARAH E. CLINTON, OF GRAND RAPIDS, WISCONSIN.

FRESH-AIR HOOD.

1,108,972.

Specification of Letters Patent.

Patented Sept. 1, 1914.

Application filed June 8, 1912. Serial No. 702,486.

To all whom it may concern:

Be it known that I, SARAH E. CLINTON, a citizen of the United States, residing at Grand Rapids, in the county of Wood, State 5 of Wisconsin, have invented certain new and useful Improvements in Fresh-Air Hoods; and I do hereby declare the following to be a full, clear, and exact description of the invention, such as will enable others skilled 10 in the art to which it appertains to make and use the same.

The present invention is directed to improvements in fresh air hoods, and has for its object to provide a device of this character 15 so constructed that the face of a person may be so arranged in relation thereto that fresh air may be obtained without exposing any other part of the body.

A further object of the invention is to provide a device of this character which may be 20 adjusted to fit any size window frame, and one in which the supply of fresh air may be regulated.

With these and other objects in view, this 25 invention resides in the novel features of construction, formations, combinations and arrangements of parts to be hereinafter more fully described, claimed and illustrated in the accompanying drawing, in which:

30 Figure 1 is an elevation of the device taken from the inside of a room. Fig. 2 is a sectional view on line 2—2 of Fig. 1. Fig. 3 is a similar view on line 3—3 of Fig. 1. Fig. 4 is a longitudinal sectional view. Fig. 35 5 is a front elevation. Fig. 6 is an end view.

The device consists of pair of slidably connected plates 1 and 2, respectively, said plates being thus adjusted to window frames of various sizes. To retain the device in 40 place it is only necessary to adjust the plates to the width of the window frame, lower the lower sash until the bottom rail thereof rests upon the upper edges of said plates.

A circular air inlet opening 3 is formed 45 in the plate 1. Formed above and below the opening 3 are guide-ways 4, and in which is slidably mounted a door 5, said door being provided with a handle 6, so that the same may be conveniently moved, thus entirely closing the opening 3, or partially closing the same so that the ingress of fresh air may be regulated. Further, the door 50 may be moved so that the opening 3 is en-

tirely open and this is accomplished by guides 7 which are carried by the plate 2, 55 whereby the door may be moved from the plate 1 to the latter.

Hingedly mounted on one edge of the plate 1 is a bar 8, which is adapted to slidably receive the rectangular eyes 9 carried 60 by the wooden hoops 10 of the hood 11, said hoops being inclosed by a covering 12, thus permitting the same to be readily folded when not in use.

The hood 11 is provided near its inner 65 end, and in the under surface of the cover thereof with an opening 13, the sides of which may be regulated to fit the face of the person by draw strings or in any other suitable manner, or if desired the head of 70 the user may be passed through said opening and into the interior of said hood.

By providing the bar 8 it will be seen that the hood 11 may be swung away from the plate 1 when it is desired to adjust the 75 door 5, and when the device is in use the bar is shifted so that the opened end of the hood 11 will be in direct communication with the inlet opening 3.

From this construction it will be seen 80 that a device of this type has been produced, which may be easily adjusted to windows, and one which may be easily and conveniently folded when not in use.

What is claimed is:—

In a device of the class described, the combination with a plate which is provided with an air inlet, of a bar pivoted to the plate, and a plurality of alined hoops, certain of which bear rings for slidably engaging the bar, a cover of flexible material inclosing all of the hoops to provide a hood open at one end, said hood being adapted to telescope upon sliding the rings upon the bar, whereby the open end of said 95 hood may be swung from registry with the air inlet, said hood being also adapted when extended to have its open end register with said inlet.

In testimony whereof, I affix my signature, in presence of two witnesses.

SARAH E. CLINTON.
